UNITED STATES PATENT OFFICE

ANDRÉ M. MERTZANOFF, OF NEW YORK, N. Y., ASSIGNOR TO AMERICAN RADIATOR COMPANY, OF NEW YORK, N. Y., A CORPORATION OF NEW JERSEY

DESIGN FOR A RADIATOR SECTION

Application filed February 8, 1927. Serial No. 20,653. Term of patent 14 years.

To all whom it may concern:

Be it known that I, ANDRÉ M. MERTZANOFF, a subject of the King of Greece, residing at the city of New York, borough of Manhattan, in the county and State of New York, have invented a new, original, and ornamental Design for Radiator Section, of which the following is a specification, reference being had to the accompanying drawings, forming a part thereof.

In the drawings—

Figure 1 is a front or face view showing a radiator section showing my new design;

Fig. 2 is an edge view thereof;

Fig. 3 is a top view;

Fig. 4 is a vertical section on the line 4—4

of Fig. 1, showing the external contours of the intermediate transverse connecting members, and the form of the vertical openings between said members;

Fig. 5 is an enlarged detail transverse section on the line 5—5 of Fig. 1, showing the external contour of vertical tubular members, and

Fig. 6 is an enlarged detail transverse section on the line 6—6 of Fig. 1 showing the external contour of the upper and lower header-members.

I claim:

The ornamental design for a radiator section, as shown.

ANDRÉ M. MERTZANOFF.
